LOADER

Clarence B. Richey, Quincy, Ill., assignor to Electric Wheel Company, Quincy, Ill., a corporation of Illinois

Application June 8, 1944, Serial No. 539,304

16 Claims. (Cl. 214—131)

This invention is directed to a loader that may be conveniently attached to a standard make of tractor and which is so arranged as to be connectible with the tractor power lift for its operation for loading or unloading as the case may be.

There are a number of loaders on the market which attach to the tractors for use in loading manure, hay or the like, as general utility equipment on a farm. Some are attachable to the front end of a tractor and others are made to attach to the rear end of a tractor. It has been found from experience that front end loaders have proven expensive for ordinary practical farm use since they require many parts with special framework, hoists, etc., making the same cumbersome, limiting the field of operation thereof considerably and also cutting down the flexibility of operation of such a unit as well. Many difficulties have likewise presented themselves with the use of the types of rear loaders now on the market, the main drawback in the past having been the cost of such loaders arising because of their complex constructions and bulkiness.

One of the main objects of the utility loader of this invention is to provide one that may be used with a small size tractor such as Ford-Ferguson tractor, with the loader so designed as to operate in confined quarters as under roofs, etc., and in many places where other loaders cannot be practically used. The particular loader is designed to deliver loaded material at a height of 46" above the ground which gives ample clearance for the ordinary standard manure spreader box, the sides of which normally terminate about 42" above the ground level.

Another advantage of the present loader that facilitates its use under low clearance conditions is the embodiment of mechanism including a pusher for discharging material directly off the top ends of the tines of the fork of the loader, to thereby eliminate the use of a loading fork of the tilting or rocking type. Obviously, a loader of the tilting fork type requires considerable additional head room to permit the loading fork to dip forwardly into a manure spreader box or other receptacle sufficiently to cause the material to move therefrom by gravity. This head room must be sufficient to allow the fork end to clear the rising level of material as the box or receptacle gradually fills.

With the loader design herein presented, the fork tip or tine ends need only be raised sufficiently to clear the top of the box sides or the sides of a receptacle, which normally disposes

the loading fork in an upwardly inclined position, and the pusher then travels along the fork moving and substantially lifting the load along the surface of the fork to spill the material progressively off of the fork end into the box or upon the material already loaded therein.

By comparison, for practical operation, it is apparent that a loader of the tilting fork type requires considerably longer framework thereby

10 adding to the cost of making the same, and since too much additional weight is not desirable in a loader suspended from the rear end of a tractor, a relatively long framework within reasonable weight limits will lack the necessary rigidity and stability necessary for the loading fork supports and associated parts. Furthermore, a longer frame and fork assembly of a loader requires greater turning clearance when the tractor is in operation.

15 20 In the loader herein submitted, the lifting links or framework that actuates the loading fork is comparatively short and compact whereby a well stabilized loader is attained that will have very little, if any, appreciable side sway, or swing

25 30 when being turned by the tractor while the loader is in action at the rear end of the tractor. A direct advantage inherent in a loader having a short lifting framework and wherein the load is carried as closely as possible to the rear axle of the tractor, is that the possibility of overbalancing the tractor is avoided and also larger amounts of material can be lifted because of greater leverage.

35 40 The compactness of the instant loader reduces wear and tear on the loader parts to a substantial minimum, due to its good stability, thereby adding considerably to the length of service of such a unit and by the same token avoiding breakdowns while in use during loading and spreading operations.

45 50 A further advantage of the loader of the present construction is that it is so designed as to be easily attached to or removed from a conventional type of tractor without necessitating any change in the tractor or its parts or in the functions thereof.

55 Another object is to provide a loader that may be manipulated by the conventional tractor power lift. Dual use is made of the power lift by providing suitable mechanism to cause the lift to raise the loaded fork and to subsequently bring the power lift into action a second time to actuate the pusher for discharging loaded material from the fork at a predetermined time or location.

Certain other features are also incorporated in

the loader as will hereinafter be mentioned in the detailed description of a preferred embodiment of the invention. In this connection, attention is also directed to the fact that the fork can be easily converted into a scoop or shovel for handling finer materials such as dirt, sand, gravel or stones, this conversion being accomplished by securing suitable plates to the fork structure.

All other improvements and advantages relating to the loader and its aggregate mechanisms will therefore appear in the following description thereof having reference to the accompanying drawings of the device constituting a workable disclosure thereof.

In the drawings:

Fig. 1 is a longitudinal cross-sectional view through the rear axle of a conventional tractor illustrating a preferred embodiment of loader attached to such tractor and connected with the power lifts thereof; such loader having the respective parts thereof and the loading fork disposed in lowered and normal loading position;

Fig. 2 is a plan view of the mechanism illustrated in Fig. 1 with the tractor wheels not shown and substantially as viewed along the line 2—2 in Fig. 1;

Fig. 3 is a front elevational view of the loading fork structure and its associated push-off with the respective parts in the same position as the Fig. 1 showing of the loader;

Fig. 4 is a small detailed view of the links and parts which are attached to the power lift arm at one side of the tractor and substantially as viewed along the line 4—4 in Fig. 1;

Fig. 5 is a view similar to that illustrated in Fig. 1 with the loading fork in raised and load transporting position but with the push-off still in retracted relation;

Fig. 6 is a fragmentary portion of the tractor and its connected links illustrating a position of the parts immediately prior to the operation of the push-off.

Fig. 7 is a fragmentary side elevational view also corresponding with the views in Figs. 5 and 6 but illustrating the linkages in a position wherein the push-off has been moved to the extreme load discharging point on the loading fork;

Fig. 8 is a small fragmentary rear elevational view of the tractor casing illustrating a modified construction of latch means for the latching link which normally holds the fork in raised and load transporting position;

Fig. 9 is a plan view of the modified construction illustrated in Fig. 8;

Fig. 10 is a fragmentary plan view of the loader and a portion of the tractor to illustrate the use of stabilizing mechanism in connection with the fork;

Figs. 11 and 12 are fragmentary diagrammatic side views of the mechanism in Fig. 10, but showing two positions thereof;

Fig. 13 is a partial plan view of a modified arrangement of the fork latching means to act as fork stabilizing structure; and

Fig. 14 is a fragmentary side view of a portion of the mechanism in Fig. 13.

In Figs. 1 and 2 a conventional form of tractor has been generally indicated at 15, the forward portion of the tractor having been omitted, with the power transmission casing 16 indicated enclosing the usual driving mechanism for the tractor axles 17, one wheel 18 being illustrated in Fig. 1 on the far side of the tractor. The loading fork 20 of the loader is carried by the power transmission housing and by its associated parts, and

this fork operates vertically just beyond the peripheries of the tractor wheels while the mechanism supporting the loading fork is compactly and conveniently confined between the protective shielding of the tractor wheels as is readily illustrated in Fig. 1.

The fork 20 per se may be constructed in many ways and of materials which are easily obtainable. The present construction of fork has proven very efficient and relatively inexpensive and is best illustrated in Figs. 1, 2 and 3. This fork is of welded construction having two upright corner standards 21 and 22 welded to the outer fork tines 23 and 24 respectively, the latter being of angle iron construction. Angles 25 and 26 connect the standards 21 and 22 at the tops and bottoms respectively, and a plurality of intermediate tines 27 also of angular construction are secured to the lower cross angle 26 in spaced relation between the outer tines 23 and 24. Intermediate angles such as 28 are welded between the respective fork tines forwardly of the cross angle and toward the working end of the fork, and a reinforcing strap 30 extends across the under surfaces of such tines to additionally reinforce the same against excessive spreading during the loading operation.

Referring to Figs. 1 and 3, it is to be noted that the fork has been illustrated as provided with two or more skids such as 31 and 32 for the purpose of relieving the linkage supporting the loading fork of excessive strain when the fork is being backed into a load, Fig. 1 illustrating the fork as angularly disposed with respect to the general horizontal ground surface. The use of skids such as 31 and 32 is optional and they may be detachably secured to be added when desirable for various conditions of operation.

By supporting the loading fork from the tractor at the particular angle illustrated, the fork tears the material loose as the tractor backs the fork into the piled material. Subsequently, the lifting links are only subjected to the weight of the fork and its load as the fork is being raised and such links need not also sustain the additional force necessary for pulling or loosening the material on the fork from the aggregate of material disposed upon the ground. It has been found that by having the tines resting substantially upon the ground and in parallel relation thereto that the fork merely pierces the load adjacent the ground and does not loosen the portion of material to be raised by the fork from the piled material adjacent thereto. In the latter case it is necessary for the lifting links to cause the separation of the loaded material from the piled material obviously producing an undesirable mechanical arrangement. Therefore, by constructing the fork as shown in Fig. 1 the loading is made much simpler and the linkages are spared of this additional strain due to separating the loaded material from the piled material.

As best seen in Figs. 1, 2 and 3, the supporting links of the fork are four in number comprising a pair of upper links 33 and 34, and a pair of lower links 35 and 36. The fork ends of the upper links 33 and 34 are pivotally connected by pins 37 and 38 to brackets 40 and 41 which are secured to the cross angle 25. The tractor ends of the links 33 and 34 are pivotally connected by means of pins 42 and 43 to brackets 44 and 45 secured by saddles such as 46 and the bolts 47 and 48 to the axle housings 50 of the tractor 15. Obviously, the fixtures comprising the brackets 44 or 45 and the

saddles 46 and their connecting bolts may be left on the tractor axle housings whenever the loading fork and its associated linkages are removed therefrom.

The fork ends of the lower links 35 and 36 are pivotally mounted upon the pins 51 and 52, see Fig. 3, supported upon the U-shaped brackets 53 and 54 secured to cross angle 26 of the fork. The tractor ends of the links 35 and 36 are carried upon studs 55 and 56 suitably secured to the power transmission tractor housing 16. Collars such as 57 and 58 provided with conventional set screws may be used to hold the links 35 and 36 upon their respective tractor pivot pins 55 and 56 thereby providing an easy means for removing the links when the loading fork is being detached from the tractor.

The loading fork of the present construction is very compact and the linkages are all relatively short, all due to the fact that this fork is not of the tilting type of construction but embodies the use of a push-off for discharging the load off of the end of the fork. Such push-off is generally indicated at 60 in Figs. 1, 2 and 3 and consists of a steel plate 61 having its upper edge 62 bent toward the tine end of the loading fork as best seen in Fig. 1, such plate being reinforced at its lower edge by a cross angle 63 with a pair of spaced angles 64 and 65 vertically disposed as illustrated in Figs. 1, 2 and 3.

The push-off 60 is made to ride upon the upper edges of the tines and it will be noted that the outer tines 23 and 24 are greater in vertical dimension than the intermediate tines 27. By this construction, the push-off is guided between the upstanding edges of the outer tines 23 and 24 and rides upon the upstanding edges of the intermediate tines 27 during the operation thereof.

A pair of links 66 and 67 are secured to the angles 64 and 65 of the push-off and are stabilized by the means of the braces 68 and 70 respectively. A set of arms 71 and 72 are pivotally connected by means of pins 73 and 74 respectively to the outer ends of links 66 and 67. Arms 71 and 72 are secured to a cross-shaft 75 by welding or in any suitable manner and the shaft 75 is journaled at the upper ends of the standards 21 and 22 of the fork in bearings 16 and 77, each of which are secured to the standards by means of U-bolts such as 78 and appropriate nuts 80.

Therefore, from the above description in connection with the push-off it will be noted that the movements of the push-off 60 will be controlled by the rotary movements of the shaft 75 through the instrumentality of the linkages described. The push-off 60 will normally be maintained in its retracted and inoperative position illustrated in Fig. 1 by means of a tension spring 81 secured at its lower end to the cross angle 26 by the eye bolt 82 and at its upper end by means of a link 83 to the outer end of an arm 84 secured to the cross shaft 75.

Various means may be provided for rocking the shaft 75 against the action of the spring 81 to cause the connected links to move the push-off toward the outer end of the tines for discharging the load. In the present construction a pair of links such as 85 and 86 are pivotally connected at 87 and 88 to the ends of arms 90 and 91 also suitably secured to the rock shaft 75. To reinforce the connection of the links 85 and 86 with the rock shaft as well as to add rigidity to the arms 71 and 72, the pins 87 and 88 extend through ears 92 and 93, welded to the arms 71 and 72 respectively. The manner in which the push mem-

bers or links 85 and 86 are operated will herein-after be explained in connection with the operation of the lifting fork.

There are various forms of lifts or other equivalent mechanisms associated with conventional forms of tractors that are used in connection with implement work in the field. The tractor illustrated is of the Ford-Ferguson type and has as normal standard equipment a pair of pivotally carried arms 100 and 101 that are hydraulically operated and such arms being best illustrated in Figs. 1 and 2. These arms are normally operated through manual control means not illustrated in the present disclosures and although the arms 100 and 101 may be raised or lowered within certain limits under manual control or may be moved to various intermediate angular positions, the present loader has been designed to utilize the full movement of these arms from their normal inoperative and down positions to their full up and raised positions. There is no need for any intermediate position with the present device for loading spreaders.

A pair of lifting chains such as 102 and 103 are secured to the ends of the arms 100 and 101 by means of suitable clevises 104 and 105; while the fork ends of these chains are connected to the links 106 and 107 also carried by the pins 51 and 52. Auxiliary branch chains 108 and 109 are connected intermediate the length of the chains 102 and 103 as shown in Figs. 1 and 2 and connect with the U-shaped members 110 and 111 respectively. The U-shaped links 110 and 111 are welded or otherwise fastened to brackets 112 and 113 which are respectively bolted to the links 35 and 36. These brackets 112 and 113 carry a cross slat 114 welded thereto which forms the stabilizing means for the links 35 and 36 and such slat also has an intermediate twisted portion 115 to which can be secured an implement's clevis straps. Such a draw bar was provided for use in drawing implements or other vehicles while the fork is attached and which draw bar is accessible when the loading fork is held in raised position as best illustrated in Fig. 5.

The use of the dual or Y chains at each side of the loader is for the purpose of obtaining better mechanical advantage during the initial lifting action of the loading fork as brought about by the movement of the arms 100 and 101. The pull through the chains 102 and 103 by reason of their attachment adjacent the fork as shown in Fig. 1 provides a greater lifting leverage and relieves the arms 100 and 101 of excessive initial strain in raising the fork from rest and in loading position by reason of being more remotely connected from the pivotal points of the fork supporting links. As the fork is being raised into carrying position, there will be a point at which both of the chains 102 and 103 and the chains 108 and 109 will all carry the load equally and as the fork is lifted still further the entire load will then be raised through the auxiliary chains 108 and 109 and the portions of the chains 102 and 103 which connect the former chains with the arms 100 and 101. This latter action is also well illustrated in comparing Figs. 1 and 5 which show the two relationships between the chain actions.

Referring to Figs. 1, 2 and 4 it will be seen that the arms 100 and 101 are also further provided with links and pin means for coacting with the push bars or links 85 and 86 for manipulating the push-off of the loading fork. The arm 100 is provided with links or braces 120 and 121, the former being bolted to the pivotal end of arm

100 while the arm 101 is secured to the swinging end of the arm 100, such links 120 and 121 terminating and being secured by means of a cross pin 122 forming a rigid triangular construction directly movable with the arm 100 as the latter is swung about its pivotal axis. Similarly, arm 101 is also provided with links 123 and 124 supporting and connected by a pin 125. It is the pins 122 and 123 which cooperate with the ends 126 of the two push bars or links 85 and 86 to cause 10 rocking of shaft 75 and the resultant operation of the push-off on the loading fork. Referring to Fig. 2 it will be seen that the links 85 and 86 are laterally positioned to be in alignment with the space between each of the pairs of links associated with the arms 100 and 101. Furthermore, when the loading fork is in lowered loading position as shown in Fig. 1 both of the links 85 and 86 rest upon the peripheries of the axle housings 50 as shown. Rods 127 and 128 are welded to the links 85 and 86 to form projecting members which ride between the respective links associated with each of the arms 100 and 101 to thereby normally maintain the links 85 and 86 in operative alignment to be acted upon by the pins 122 and 125 during the portion of the cycle of operation when the push-off is being actuated.

As the loading fork is being operated from its loading position in Fig. 1 to the raised position illustrated in Fig. 5 it will be seen that the links 85 and 86 that act as push bars for operating the push-off of the loading fork are then positioned clear of their normal peripheral contact with the axle housings 50 and now rest upon their respective coacting pins 122 and 125 as shown in Fig. 5. It is essential that the links 85 and 86 are so designed that the notches 126 are carried high enough by the axle housing that the pin 122 contacts the links 85 and 86 below and in back of the notch 126 as the fork is lifted. With this arrangement it is possible in the present device to maintain the fork in raised load carrying position to permit freedom of use of the arms 100 and 101 to perform a further function, namely, that of operating the push-off. This locking of the loaded fork is accomplished by means of a latch link 130 pivotally connected at 131 to the bracket 132 carried by the fork framework. This link 130 is notched as at 133 for coaction with a pin 134 which forms a part of the mechanism 135 normally used in implement work, but which pin has no other function in the present apparatus. This pin 134 merely forms a convenient usable means that is present on the tractor construction shown which can be adapted for latching purposes in cooperation with the slot 133 in the link 130. When the loading fork is lifted into the raised position illustrated in Fig. 5 which position also signifies the limit of operation of the arms 100 and 101 in their raised positions, the notch 133 of the link 130 will drop over the pin 134 as shown in Fig. 5 with just enough clearance between the notch and the pin to insure definite latch action. Obviously, the reversal of motion of the arms 100 and 101 in a clockwise direction as shown in Fig. 5 will now cause the link 130, by reason of its notched engagement with the pin 134, to hold the fork in its raised position while the arms 100 and 101 and their connected links will now return to their initial positions as illustrated in Figs. 1 and 6. To hasten the return action of the arms 100 and 101, a suitable spring or two such as 136 and 137 are connected with ears 138 and 140 on the tractor casing 18, such ears being fixedly secured to links 120 and 123.

This return of the arms 100 and 101 to their initial positions with the lifting fork and its load locked and latched in their raised positions permits the second step in the operation of the device well illustrated in Fig. 6.

Referring now to Fig. 6 it will be seen that the pin 122 and the end 126 of the push bar 85 are now positioned for cooperation to actuate the push-off. Upon the manipulation of the manual means for again causing the arm 100 to swing in a counter-clockwise direction, the pin 122 will now engage the end 126 of the push bar 85 whereupon the shaft 75 is then rocked in a counter-clockwise direction. Obviously, the pin 125 on the opposite side of the tractor will also engage the end of the push bar 86 in the same manner. As shaft 75 rocks upon its bearings the push-off will be moved outwardly along the tines of the lifting fork through the linkages connected between the shaft 75 and the push-off 60. Various positions of the push-off have been indicated in the illustration in Fig. 7. In Fig. 7 the normal retracted position of the push-off is indicated by the reference numeral *a*, and the broken line positions 15 indicated by *b* and *c* are two intermediate positions in the travel of the push-off toward the outer end of the fork. The full line position indicated by *d* is the foremost load discharging position of the push-off. It will be noted that the links 66-71 and 67-72 have been designed and arranged as to cause the push-off to assume the reclining angularities illustrated in the intermediate position *a* and *b*. This has been done for the purpose of maintaining the push-off solidly 20 against the surface of the tines and to prevent any tendency of the push-off to slide over or above the load during the power stroke that moves the load off the end of the tines of the fork. A portion of the side of a manure spreader is also diagrammatically indicated at *L* in Fig. 7 to show the relation of the loading fork to the spreader and the function of the push-off in precipitating the load over the side into the spreader without 25 requiring the use of an extremely long fork or fork supporting framework as in the case of tilting forks.

The release of the latch link 130 is obtained through novel means immediately succeeding the discharge of the load as illustrated in Fig. 7 and after the push-off has attained the full-line position indicated by *d* in Fig. 7. This is accomplished by the use of a spring 141 having one end connected at 142 to the link 130, and a chain 143 connects the other end of the spring to a pin 144 secured to the rock shaft 75. As seen in Fig. 1, the overall length of the spring 141 and the chain 143 is so arranged that no tension will be exerted upon the link 130 until the loading fork has been moved into the position illustrated in Fig. 7. When the parts are positioned as in Fig. 7 the latch link 130 is still supporting the weight of the loading fork due to the cooperative engagement of the notch 133 in the latch link with the pin 134 on the tractor. However, as soon as the arm 100 is caused to swing a slight additional amount as is necessary to attain the full up position as illustrated in Fig. 5, the load of the fork and its associated links will again be transferred to the chain as previously described. At 30 this time, the latch link 130 will now be free of the pin 134, and since the link 130 will now be under the pulling action of the spring 141 the link will be caused to disengage from the pin 134 unlatching the loading fork from the tractor. Thereafter, upon operation of the arms 100 and 35

101 in a clockwise direction, the loading fork may then again be lowered into the loading position illustrated in Fig. 1 terminating the cycle of operation as hereinbefore explained and beginning another similar cycle of operation. During the return of the fork to its initial loading position the spring 81 retracts the push-off by acting on the cross shaft through the arm 84.

Attention is now directed to the illustration in Fig. 5 wherein the latch link 130 is shown as down and in engagement with the pin 134 in a position to latch the loaded fork upon reversal of movement of the arms 100 and 101. When the parts are in this position in Fig. 5 the rock shaft 75 has not been actuated and therefore pin 144 is disposed in its original position and no tension is exerted upon the spring 141 through the instrumentality of the chain 143. However, when the parts are in the raised position illustrated in Fig. 7 and the push-off has been actuated into the full line position the pin 144 will rotate with the shaft 75 to wind the chain 143 partially upon such shaft whereupon tension is now exerted upon the spring 141 and such tension is transmitted to the link 130. Link 130 will then be released when the mechanism is in the position illustrated in Fig. 7 while the same will not be released nor drawn away from the pin 134 when the parts are in the positions indicated in Fig. 5. To limit the movement of the bracket 130 away from the pin 134, a small bracket 145 of U-shaped construction is secured adjacent pin 134 and positioned to overlie the path of movement of the link 130.

Referring now to Figs. 8 and 9, another alternative construction of means for supporting the latch pin in the path of the latch link 130 has been illustrated. In this case a pair of brackets 146 and 147 are conveniently bolted to the top of the casing 16 of the tractor 15 and support a common pin 148 therebetween for latching engagement with the notch 133 in the link 130. A suitably bent guide rod 150 is connected with each of the brackets and performs the same function as the bracket 145 to prevent excessive outward movement of the link 130 about its pivotal fork mounting, under the action of the spring 141 upon releasing the latch link for the purpose of permitting the fork to assume its original loading position. The shape of the brackets in Figs. 7 and 8 have been illustrated for use in connection with the tractor shown in the preferred form. The brackets 146 and 147 are shaped to bridge the mechanism 145 and merely illustrate another means of supporting the pin for latching purposes in connection with the attached loading fork. Obviously, any suitably mounted pin on any portion of the tractor cooperating with the latch link illustrated will operate and act in the same capacity as the pin 134 in the preferred form, and the pin 148 in the modified form of such a construction.

It will be obvious that various changes may be made in the link construction illustrated. For example the arms connecting shaft 75 with the push-off may be of any cross-sectional construction to obtain stability and the same applies to the links 33, 34 and 35, 36 which pivotally support the fork member. Furthermore, the push-off units 85 and 86 may also be made of different cross-sectional construction than that shown. It is seen that all of the links connected between the tractor and the fork are presently made of suitably proportioned strap steel bars primarily to obtain a fairly light weight structure and for reducing the cost thereof as well as to enhance the

efficiency and speed of operation of the fork under the action of the power arms 100 and 101.

There are ways if desired in which stability may be added to the structure illustrated particularly to resist side sway when the fork is loaded when in raised transportable position in back of the tractor. One construction is illustrated in Figs. 10, 11 and 12, wherein the use of chains such as 152 and 153 are connected between brackets 154 and 155 conveniently secured to the lower swingable links 35 and 36 of the fork. The chains 152 and 153 may be secured to the tractor casing by any suitable adjustable fastening means 156 and 157, such adjustable means permitting a certain amount of regulation of the slack in these chains to allow perfect functioning thereof. As diagrammatically illustrated in Figs. 11 and 12 it will be seen that when the fork is in the lower position as also shown in Fig. 1, the chains will be fairly taut between their respective points of support to stabilize the fork when loading. When the fork has been raised as in Fig. 12 into the load transporting position which is also equivalent to the Fig. 5 position, the chains will again be substantially taut between their respective connecting points on the links and tractor casing. Therefore, any quick turning of the tractor and possible swaying of the rear end of the fork and its supported load will be stabilized through the action of the chains as will be readily conceivable.

Another way of stabilizing the fork when in carrying position is illustrated in Fig. 13 by the use of a double latch link construction in place of the original single link 130 illustrated in the preferred form of loader. In the latter construction in Fig. 13, a pair of links such as 160 and 161 are provided to coact between the fork 20 and the tractor housing 16. These links are spaced as shown and connected by suitable cross members 162 and 163 and through the diagonal braces 164. In this case, the spring 141 is secured at 165 to one of the cross braces as shown and acts in the same manner as hereinbefore for releasing the pair of latch links. In Fig. 13 the latch links 160 and 161 are pivotally connected to the loading fork at points 166 and 167 while the outer ends cooperate with latching pins 170 and 171 supported upon the tractor casing 16 by the brackets 172 and 173. Bent rods such as 174 and 175 are secured to the end portions of the brackets and overlay the paths of the swinging latch links 160 and 161 as best illustrated in Fig. 14 for the purpose of limiting the movement thereof away from their respective latch pins under the action of the spring 141. It is also possible to use both of the stabilizing ideas presented in Figs. 10 and 13 in combination if that is desirable.

The utility loader described is designed for the purpose of having a loader of a detachable character that will be within the reach of any small farm owner and at the same time to supply such owner with a device that saves considerable labor or additional help to carry on many tedious farm tasks. Furthermore, the device is adaptable to relatively small tractors and as shown may be operated through the double manipulation of a single power lift supplied with a tractor as standard equipment thereon.

Summarizing the operation of the loader in connection with the conventional tractor shown it is seen that the first step will be to back the tractor with the fork into the material being loaded as shown substantially in Fig. 1. Then by operating the manual lever for raising the

lifting arms the fork is raised into the position illustrated in Fig. 5 which suspends the load in carrying position. The operator can then again manipulate the lever for lowering the arm which locks and latches the load into the position illustrated in Fig. 6, the arms returning to their initial lowered position as the tractor is driven to the point of delivery of the load. When the tractor arrives at the point of discharge the fork is positioned accordingly through steering the tractor and at this point the operator will again operate the manual lever for raising the arms which will operate the push-off and discharge the load in the manner illustrated in Fig. 7. Thereafter the fork will automatically release itself upon completion of the upper stroke of the arms 100 and 101 whereupon the operator may carry the fork in this raised position and may subsequently operate the lever to allow the fork to lower as he again drives the tractor to the loading point to obtain another load of the material.

It is to be understood that the foregoing descriptions and disclosures are all more or less specifically directed to exemplary constructions of the present tractor loader and that various changes and modifications are contemplated which will produce equivalent mechanisms or mechanical structures that shall function or produce the same operative requirements in a like manner as will the mechanisms described. Therefore, it is obvious that the present form, construction, or combination of parts described and illustrated are not to be limited to the exact disclosures excepting insofar as such structures shall be defined and limited by the breadth and scope of the appended claims.

What I claim is:

1. A loader for a tractor having power lift means, comprising a fork movably mounted upon said tractor, a push-off on said fork, operable means connected between the fork and said power lift means to raise said fork, a latch means to lock said fork in raised position, said operable means being rendered ineffective by said latch means in response to the movements of said power lift means after said fork is locked, and push-off actuating means automatically connectible with said power lift means to operate said push-off when said fork is disposed in raised latched position.

2. A loader for a tractor having power lift means operable between certain limits of movement, comprising a load carrying member supported upon said tractor for movement relative thereto, a push-off on said load member, operable mechanism connected between the load member and said power lift means to move said load member into raised load transporting position during movement of said power lift means in one direction, lock means to hold said load member in raised load carrying position, said lock means functioning to render said operable mechanism ineffective to allow said power lift means to move in the opposite direction, and push-off actuating mechanism connectible with said power lift means to be operated by said lift means as the latter again moves in said one direction to operate said push-off when said load member is in said raised and locked position.

3. In a loader for a tractor having power lift arms, a loading fork, a material push-off on said fork, links for pivotally supporting said fork from said tractor, chain means connected between said fork and the power lift arms for rais-

ing the fork, push-off actuating means disposed for connection with said power lift arms, locking means for holding said fork in raised position independently of said power lift arms, and means carried by said power lift arms and adapted for engagement with said push-off actuating means to cause the latter to move said push-off and discharge the loaded material from said fork, said chain means permitting said arms to so function while said fork is locked in raised position, and release means connected with said locking means to render the latter ineffective after the material is discharged from said fork.

4. In a loader for a tractor having power lift arms movable between two positions, a loading fork swingably supported upon said tractor, a push-off carried upon said fork, lifting means connected between said fork and the lift arms to dispose said fork in loading position upon the ground when said arms are in one position and to dispose said fork in material transporting position when said arms are in their second position, locking means for holding said fork in transporting position independently of said lift arms when the latter move to said second position, and co-acting mechanisms connected with said push-off and said lift arms respectively to move said push-off along said fork to discharge material therefrom as said arms are again moved from said one to the other of their positions.

5. In a loader for a tractor having power lift arms movable between two positions, a loading fork swingably supported upon said tractor, a push-off carried upon said fork, lifting means connected between said fork and the lift arms to dispose said fork in loading position upon the ground when said arms are in one position and to dispose said fork in material transporting position when said arms are in their second position, locking means for holding said fork in transporting position independently of said lift arms when the latter move to said second position, and co-acting mechanisms connected with said push-off and said lift arms respectively to move said push-off along said fork to discharge material therefrom as said arms are again moved from said one to the other of their positions, and means controlled by the movement of one of the aforesaid coacting mechanisms to release said fork locking means when said lift arms are again disposed in their aforesaid second positions to subsequently lower said fork into contact with the ground.

6. In a loader for a tractor having lift arms operable from lowered to raised positions, a loading fork swingably supported upon the tractor, a push-off on said fork to discharge loaded materials therefrom, lift means connected between said lift arms and the fork to raise the latter from loading position to load carrying position, operating mechanism carried by said fork and connected with said push-off to move the latter including actuators disposed for engagement by said lift arms, and connectible means carried by said tractor and said fork respectively and adapted for cooperation with said lift arms whereby said fork is automatically suspended in raised position from the tractor after said lift arms are operated from lowered to raised positions, and whereby said arms are rendered operative to engage said push-off actuators to operate said push-off to discharge the loaded material from said fork.

7. In a loader for a tractor having lift arms operable from lowered to raised positions, a loading fork swingably supported upon the tractor,

a push-off on said fork to discharge loaded materials therefrom, lift means connected between said lift arms and the fork to raise the latter from loading position to load carrying position, operating mechanism carried by said fork and connected with said push-off to move the latter including actuators disposed for engagement by said lift arms, and connectible means carried by said tractor and said fork respectively and adapted for cooperation with said lift arms whereby said fork is automatically suspended in raised position from the tractor after said lift arms are operated from lowered to raised positions, and whereby said arms are rendered operative to engage said push-off actuators to operate said push-off to discharge the loaded material from said fork, and release means cooperating with one of said connectible means to disengage the latter and to transfer the fork suspension from the tractor back to the lift arms.

8. In a loader for a tractor having lift arms operable from lowered to raised positions, a loading fork swingably supported upon the tractor, a push-off on said fork to discharge loaded materials therefrom, lift means connected between said lift arms and the fork to raise the latter from loading position to load carrying position, operating mechanism carried by said fork and connected with said push-off to move the latter including actuators disposed for engagement by said lift arms, and connectible means carried by said tractor and said fork respectively and adapted for cooperation with said lift arms whereby said fork is automatically suspended in raised position from the tractor after said lift arms are operated from lowered to raised positions, and whereby said arms are rendered operative to engage said push-off actuators to operate said push-off to discharge the loaded material from said fork, and release means cooperating with one of said connectible means to disengage the latter and to transfer the fork suspension from the tractor back to the lift arms, said release means being connected with a part of said push-off operating mechanism to automatically cause said fork load transfer to the lift arms upon completion of said load discharging function of said push-off.

9. In a loader for a tractor having power lift means, a loading fork member, link members for swingably supporting said fork member from said tractor, Y-chain means connected between two points on said members and said power lift means whereby one of the chain ends on said members is effective to initially raise the loaded fork from rest out of the piled material with a greater mechanical advantage and whereby said second chain end subsequently becomes effective to permit a greater lift of said fork, a push-off on said fork member, operating means to actuate said push-off disposed for connection with said power lift means, and coacting means carried by said fork member and said tractor respectively to lock the fork member in suspended position to release said Y-chains of their lifted loaded fork whereby said lift means may be brought into contact with said push-off operating means to actuate the latter.

10. In a loader for a tractor having power lift means, a loading fork member, link members for swingably supporting said fork member from said tractor, Y-chain means connected between two points on said members and said power lift means whereby one of the chain ends on said members is effective to initially raise the loaded fork from

rest out of the piled material with a greater mechanical advantage and whereby said second chain end subsequently becomes effective to permit a greater lift of said fork, a push-off on said fork member, operating means to actuate said push-off disposed for connection with said power lift means, and coacting means carried by said fork member and said tractor respectively to lock the fork member in suspended position to release said Y-chains of their lifted loaded fork whereby said lift means may be brought into contact with said push-off operating means to actuate the latter, and release means responsive to the movement of said push-off operating mechanism to unlock the fork member and again transfer the weight thereof to said chains after the fork member load has been discharged to permit lowering of said fork member into position to receive a new load.

20 11. In a loader for a tractor having power lift means, a fork swingably supported from said tractor, a push-off on said fork, link means connected between said lift means and said fork whereby said lift means may raise said fork into an upwardly inclined position, operable mechanism including joined links connected with said push-off and disposed for operation by said lift means after said fork is raised, said push-off comprising a generally flat load contacting member disposed substantially at right angles to said fork when retracted upon the latter to partially hold the load as said fork is raised, and said joined links of said push-off operating mechanism comprising means to force the fork contacting edge of said push-off under the load and against the surface of said fork during the discharge of loaded material from said fork.

12. In a loader for a tractor having power lift means, a fork swingably supported from said tractor, a push-off on said fork, link means connected between said lift means and said fork whereby said lift means may raise said fork into an upwardly inclined position, operable mechanism including joined links connected with said push-off and disposed for operation by said lift means after said fork is raised, said push-off comprising a generally flat load contacting member disposed substantially at right angles to said fork when retracted upon the latter to partially hold the load as said fork is raised, and said joined links of said push-off operating mechanism comprising means to force the fork contacting edge of said push-off under the load and against the surface of said fork during the discharge of loaded material from said fork, and means carried by said fork and connected with said push-off to hold the latter in inoperative retracted position and to return said push-off to such position after having discharged the fork load.

13. In a loader for a tractor having power lift means, a fork swingably supported from said tractor, a push-off on said fork, link means connected between said lift means and said fork whereby said lift means may raise said fork into an upwardly inclined position, operable mechanism including joined links connected with said push-off and disposed for operation by said lift means after said fork is raised, said push-off comprising a generally flat load contacting member disposed substantially at right angles to said fork when retracted upon the latter to partially hold the load as said fork is raised, and said joined links of said push-off operating mechanism

comprising means to force the fork contacting edge of said push-off under the load and against the surface of said fork during the discharge of loaded material from said fork, and resilient mechanism connected between said fork and said operable push-off actuating mechanism to normally maintain said push-off in retracted position upon said fork and to return said push-off to such position after discharging a fork load.

14. The combination with a tractor having power operated lift arms, of a loader having a lifting fork and a push-off on said fork, a first means connected between said fork and said lift arms for raising and lowering said fork, a second means connected with said push-off and adapted for operative engagement by said lift arms when said fork is in raised position, said second means including actuators disposed for non-engagement with said lift arms when said fork is in loading position, said actuators being wrought into a position to be engaged by said lift arms while said fork is raised, and automatic latching means for locking said fork in raised position and to permit said lift arms to engage said actuators to operate the push-off when said fork is so raised, and means responsive to the movement of said push-off to release said automatic latching means to permit said lift arms to again lower said fork through the instrumentality of said first means.

15. A tractor loader operable by power lift means of the tractor, comprising a fork, a push-

off on said fork, collapsible raising means connected between said fork and the power lift means for lifting said fork upon movement of said lift means from initial position, lock means to hold the fork in raised position, actuating means for said push-off including latch means arranged for connection with said lift means after said fork is locked, said raising means collapsing while the power lift means returns to initial position to engage the latch means of the push-off actuating means, subsequent movement of said power lift means from its initial position operating said push-off.

16. A tractor loader operable by power lift means of the tractor, comprising a fork, a push-off on said fork, collapsible raising means connected between said fork and the power lift means for lifting said fork upon movement of said lift means from initial position, lock means to hold the fork in raised position, actuating means for said push-off including latch means arranged for connection with said lift means after said fork is locked, said raising means collapsing while the power lift means returns to initial position to engage the latch means of the push-off actuating means, subsequent movement of said power lift means from its initial position operating said push-off, and release means to release said fork for lowering.

CLARENCE B. RICHEY.
